JAMES S. CROSSLEY, OF SOLVAY, NEW YORK, ASSIGNOR TO PASS & SEYMOUR, INC., OF SOLVAY, NEW YORK, A CORPORATION.

INCANDESCENT-ELECTRIC-LAMP SOCKET.

995,772.

Specification of Letters Patent. Patented June 20, 1911.

Application filed October 6, 1910. Serial No. 585,555.

To all whom it may concern:

Be it known that I, JAMES S. CROSSLEY, a citizen of the United States, residing at Solvay, in the county of Onondaga and 5 State of New York, have invented new and useful Improvements in Incandescent-Electric-Lamp Sockets, of which the following is a specification.

My invention relates to the well known 10 porcelain socket of Patent No. 568,919 to Pass and Seymour, and consists in certain improvements, particularly in the switch mechanism, whereby a double break is produced in one leg of the circuit, when the 15 current is turned off, and the danger of accidental contacts and short circuits reduced.

My invention is shown in the drawing 20 herewith in which the reference numerals of the description are used to indicate the corresponding parts in all the figures.

Figure 1 is a vertical section taken on line 1 of Fig. 3 of the assembled socket. Fig. 2 is a bottom plan of the cap. Fig. 3 is a top 25 plan of the body. Fig. 4 is a vertical section taken on section line 4 of Fig. 3 looking toward the left, for the purpose of showing the arrangement and operation of the particular parts in question when the circuit is open. Fig. 5 is similar to Fig. 4 showing 30 the circuit closed. Fig. 6 is a vertical cross section of the complete socket taken at a right angle to Fig. 1.

1 indicates the cap of the socket provided with the upper extension 2, in which is 35 formed the tubular recess 3 to receive and retain in position the conductor cords 4. The ends of the cords extend through the two separate holes 7, and enter the chamber between the cap and the body immediately adjacent to the binding screws on the respective wire terminals 5 and 6, held in position by their respective screws 8 and 9; screw 8 is inserted through the recess and screw 9 through a portion of the cap outside of said 45 recess. The wire terminal 5 is arranged on the flat supporting bed 11, and is positively insulated and cut off from adjacent metallic parts by means of the straight wall 13 having the curved end 14. This terminal is provided with an upturned tip 15 to restrain the loose conductor strands. The terminal 6 is arranged on a shoulder 17 substantially parallel and adjacent to terminal 5, but on the opposite side of the wall, and has its contact screw carrying end bent up above the level

of the terminal 5 into rather a deep channel 18, so as to be near the hole through which its conductor enters and to increase the separation between the metallic parts. 21 is a wider guide spur integral with the circumferential margin 22 of the cap and adapted to engage with a notch of similar width formed in the body; 23 is a narrow guide spur also on the marginal wall adapted to fit the notch 24 formed in the body margin 60 for the shaft of the key. 65

The upper face of the body is adapted to fit the lower face of the cap and is provided with the central tubular projection 27 for the main contact screw 28 which engages 70 with the screw hole in the wire terminal 5, thereby mechanically securing the body to the base and also forming a portion of one leg of the circuit. The head 29 of this screw acts as the center lamp terminal. Said tubular projection is connected to the margin by the wall 32, whereby the parts are strengthened. Between said wall and an abutment 33 on the margin is the notch for receiving the wide guide spur on the cap, whereby the 75 relation of the cap to the body is fixed. 80

40 indicates the mouth, or recess, on the body, for the lamp terminals here shown of the Edison type. The outer terminal, or threaded copper shell 41 is secured in position by screws 42 and nuts 43 set in recesses 44 in the upper face of the upper wall 45 of the body, and desirably covered by insulating cement to avoid all danger of accidental contact. One of these screws also 90 maintains in position the resilient copper tongue, or extension, 47, which extends upwardly from the threaded shell into the opening 48 in the transverse wall of the body and is thus electrically a part of said 95 shell and adapted to be engaged with a good wiping contact by the metallic cam 50 of the key shaft 51 when the latter is turned to close the circuit by means of the insulating thumb piece 52 on the outer end of the key- 100 shaft extending through the notch 24.

On the upper face of the body is secured the key retaining plate 55 and the main contact spring 56, by means of the nut 57 and of the single screw 58, which may be operated through the socket mouth, where its head rests in the depression 59 on the lower face of the transverse wall so as to be fully insulated from the shell flange. Said contact spring is preferably in the form of a 110

curved flat piece of copper. As best shown in Fig. 3 the solid wall 32 and the marginal base forms a corner for receiving and fixing the position of the brass plate, the copper 5 contact spring and their retaining nut. By this arrangement of parts it will be seen that the key shaft is held in position, so as to be free to rotate, in the notch 24 and the corresponding inner notch 61 by means of 10 the retaining plate 55, and the cam on the shaft is free to make engagement with the contact spring 56 through the hole in said plate. On turning the shaft and cam, at one and the same time said contact spring 15 is pushed upwardly into engagement with the wire terminal 6 and the cam, as best shown in Figs. 1 and 5, makes contact with the tongue 47 bridging the gap between said spring and tongue and closing the circuit. 20 But when the thumb piece is turned in the position shown in Fig. 4, there is a double spring break, respectively between the spring and the wire terminal on the one hand, and the cam and tongue on the other. 25 The cam is held in this position by the engagement of the contact spring, so that a double break in that leg of the circuit is maintained and insured.

Having described my invention, I claim,

30 1. In an incandescent electric lamp key socket the combination with the cap and the body having a transverse wall near its upper end, said wall being formed with an opening, of wire terminals, on the cap, lamp 35 terminals on the body, a metallic part connected to one lamp terminal and extending into said opening, means to secure the body to the cap, a suitably insulated contact spring arranged between the cap and the body, said spring being initially out of contact with any metallic part except a cam, a shaft journaled between the cap and the body, and the metallic cam on the shaft, said cam being arranged between the metallic part and the contact spring and being 45 adapted, when turned into longitudinal, circuit-closing position, to engage with both said metallic part and said spring, bridging the gap between them, and simultaneously 50 to force the spring against one wire terminal closing said second gap.

2. In an incandescent electric lamp key-socket having two main parts, the cap and the body, the combination therewith of wire 55 terminals on the cap, lamp terminals on the body, a permanent connection between one lamp terminal and the corresponding wire terminal, means to connect the cap and the body, a metal extension connected to the 60 second terminal on one of said two parts, an insulated spring suitably supported and extending adjacent to the second terminal

on the other of said two parts, a shaft journaled between the cap and the body, and a metallic cam on the shaft, said cam being 65 adapted when turned in longitudinal current closing position, to engage with both the metal extension and the spring, closing the gap between them, and simultaneously 70 forcing the spring into engagement with its adjacent terminal, closing said second gap.

3. In an incandescent electric lamp key-socket, having two main porcelain parts, the cap and the body, said body having a transverse wall near its upper end, an opening 75 therethrough and a mouth or recess in its lower portion for the lamp terminals, the combination with said two parts of wire terminals secured on the lower surface of the body and arranged substantially parallel, a 80 screw extending from said mouth through the transverse wall and engaging with the center wire terminal, a threaded shell secured in said mouth, a tongue connected to said shell and extending upwardly into the 85 transverse wall opening, an insulated contact spring secured on the upper surface of the transverse wall and extending over said opening, a shaft journaled between the cap and the body, a thumb-piece on the outer 90 end of said shaft, and a metallic cam on the shaft, said cam being adapted, when turned in one direction, to close the circuit in its leg of the circuit by making contact with the tongue simultaneously and by forcing 95 the spring against the outer wire terminal; and when turned in the other direction, to be out of contact with the tongue and to permit the spring to retract.

4. A porcelain cap for incandescent electric lamp sockets, having two holes for the conductors, a tubular extension upwardly extending from the upper ends of said holes, and, on its lower surface, an elevated bed, an adjacent shoulder, a straight separating wall between said bed and shoulder, said wall having a curved end extending around the end of the bed and, in combination with the cap, metallic wire terminals secured 100 respectively on the bed and the shoulder, on opposite sides of the wall, said terminals being arranged substantially parallel, and having their opposite ends provided with binding screws arranged adjacent to the inlet holes, and the terminal on the shoulder 105 being upwardly bent.

In testimony whereof I have signed my name to this specification in the presence of two subscribing witnesses.

JAMES S. CROSSLEY.
